C. CLEVELAND.

PENCIL SHARPENER

APPLICATION FILED DEC. 6, 1919. RENEWED AUG. 20, 1921.

1,417,034.

Patented May 23, 1922.

Inventor:

Clement Cleveland,

By his Atty, J. A. Richards.

UNITED STATES PATENT OFFICE.

CLEMENT CLEVELAND, OF NEW YORK, N. Y.

PENCIL SHARPENER.

1,417,034.

Specification of Letters Patent. Patented May 23, 1922.

Application filed December 6, 1919, Serial No. 342,891. Renewed August 20, 1921. Serial No. 493,962.

To all whom it may concern:

Be it known that I, CLEMENT CLEVELAND, a citizen of the United States, residing in New York, in the county of New York and 5 State of New York, have invented certain new and useful Improvements in Pencil Sharpeners, of which the following is a specification.

My present invention relates to that class 10 of pencil sharpeners which usually have a substantially conical form and are provided with a longitudinally disposed knife-edge and an adjoining chip-space, and which sharpeners being of small dimensions are 15 convenient for carrying in the pocket, my present invention being in part an improvement on the pencil sharpener described in my copending application Serial No. 303, 473, (renewal) filed June 11th, 1919.

20 An object of my present invention is to furnish such an improved pencil sharpener in which the several details shall be so organized that the entire sharpener may be manufactured at a relatively low cost.

25 A further object is to furnish a highly effective pencil sharpener arranged for first reducing the "wood" or lead-encasing portion of the pencil, and for next sharpening or pointing the lead by a separate operation, 30 thus effecting the sharpening of the pencil by a two-member process.

35 A further object is to furnish a highly effective pencil sharpener of conical form having a plane-edge and a knife-edge arranged for first reducing the "wood" or 40 lead-encasing portion of the pencil, the lead of the pencil next being sharpened or pointed by the knife-edge in a socket for receiving and positioning the lead for 45 sharpening or pointing, which socket is formed by a member which also acts as a means for separating the plane-edge and the knife-edge so that the knife-edge is brought into proper position for coaction with the 50 plane-edge for cutting purposes, the knife-edge reacting on the separating member as a binding-spring for holding this member in position in the sharpener.

55 Further objects and advantages will be pointed out in the course of the following description.

In the accompanying drawings forming part of this specification,—

Figure 1 is a perspective view of a pencil sharpener made in accordance with, and

illustrating a preferred embodiment of, my present invention.

Fig. 2 is a longitudinal sectional view of the conical portion of the pencil sharpener and the member for separating the plane- 60 edge and the knife-edge of the sharpener.

Fig. 3 is a detail end view of the pencil sharpener.

Fig. 4 is a longitudinal sectional view on the line 4—4 of Fig. 3, looking in the direction of the arrow, showing the guide-springs.

Fig. 5 is a plan view showing the knife-edge *e*, the plane-edge *f*, and in outline the separating member *D*.

Fig. 6 is a view of the blank from which 70 the conical portion of the pencil sharpener is formed.

Fig. 7 is a plan view of the separating member *D*.

Fig. 8 is an end view of the separating 75 member *D* looking in the direction of the arrow Fig. 7, this figure being arranged in alined projection with Fig. 7, for purposes of comparison.

Fig. 9 is a side view of the separating 80 member *D* arranged in lower projection with Fig. 7.

Fig. 10 is an end view of the conical portion of the pencil sharpener on the line 10— 10 of Fig. 2, looking in the direction of 85 the arrow, the separating member *D* being removed.

Fig. 11 is an enlarged cross-sectional and fragmentary view of the upper portion of the assembled parts as shown in Fig. 2 and 90 taken on the line 11—11 of Fig. 7, for illustrating the relation of the several coacting faces whereby the cutting-edge is held under proper adjustment for use and for acting as a spring for tensioning the socket 95 member *D* in working position.

Similar characters designate like parts in all the views.

My present invention comprises the conical portion or cone *C* of the sharpener, the 100 separating member *D*, and the guide-springs or guide-fingers *3^d*, *3^e*.

The cone *C* is formed by a blank *B*, of resilient metal or material suitable for the purpose, of the shape shown in the drawings; that is, the blank *B* is a truncated segment of a circle, the arc, as *n²*, at the truncated end being concave, and the greater arc, as *n⁵*, at the other end of the segment being convex, the edges or sides of the seg- 110

ment converging from the greater arc n^3 towards the lesser arc n^2 , one of the sides or edges as e , and herein termed the knife-edge, being provided with a cutting edge e' , and the other side or edge, as f , and herein termed the plane-edge, having a non-cutting or straight face f' . The plane-edge f of the blank B is provided with a recess g for engaging the separating member D 10 therein as hereinafter stated.

Blanks for forming the guide-springs or guide-fingers $3^d, 3^e$, are provided on each side of the line of diameter of the segment, the guide-spring or guide-finger blanks being located about mid-way between the line of diameter and the respective edges or sides of the segment adjacent to the guide-spring or guide-finger blanks.

The sides or edges of the blank B are 20 rolled or pressed together by suitable means into the tubular cone C , the plane-edge f and the knife-edge e assuming, when the cone is viewed from the greater end thereof as on the line 10—10 Fig. 2, in the direction of the arrow, the positions shown in Fig. 10, that is, the knife-edge e lies slightly interiorly of the plane-edge f .

The guide-spring or guide-finger blanks $3^d, 3^e$, are forced or pressed inwardly to position for properly engaging or guiding the pencil E when the same is inserted in the cone C for sharpening.

The separating member D , is of the shape indicated in the drawings, that is, it is a 35 reversely curved member, when viewed from the side as in Fig. 1, having a somewhat curved end d' and an end d^2 , of greater curvature than the end d' , the purpose of which is hereinafter stated. The separating member D is provided with a rib or fin d^3 , Figs. 40 7, 8 and 9, which is intended to engage or be inserted in the recess g in the plane-edge f of the cone C , and to engage the interior surface of said plane-edge.

To assemble the pencil sharpener the separating member D is engaged or inserted in the recess g of the cone C , engaging the interior surface of the plane-edge f , the end d' of the separating member lying over or 50 engaging the exterior surface of the plane-edge f of the cone, and the end d^2 of the separating member lying under or engaging the interior surface of the knife-edge e of the cone. The end d^2 thus springs outwardly or presses outwardly the knife-edge and with it the cutting-edge e' from the position relative to the straight-face f' of the plane-edge f as shown in Fig. 10, to a position where the cutting-edge e' will coact with the straight face f' , as shown in Figs. 1 and 3, so that the cutting-edge e' will cut the wood or lead encasing portion of the pencil evenly and regularly, and will not gouge or bite into the wood or lead encasing portion. This adjustment is further illus-

trated by Fig. 10^a, where the face x of the separating member D is shown engaging the straight surface f' of the plane-edge f , while the face y engages the under surface of the knife edge e to support or press outwardly the knife-edge, and the face z engages, as a stop face, the cutting edge e' of the knife-edge.

The material of the cone C being of considerable resiliency the knife-edge e when so sprung or forced outwardly reacts or presses inwardly and downwardly on the end d^2 of the separating member D and provides a binding-spring for retaining the separating member D in position in the cone C .

When the separating member D is in the above described position in the cone C , the end d^2 of greater curvature than the end d' forms with the adjacent portion of the knife-edge e , a socket or means h for receiving therein the lead-end of the pencil E for sharpening or pointing the lead by means of the cutting-edge e' of the knife-edge e , this socket h being of substantially cone shape due to the curvature of the knife-edge and the tapering of the cone C and the curvature of the end d^2 of the separating member substantially as indicated in Figs. 1, 2, 3 and 5. It will be understood, of course, that in practice the exact shape, proportions and position of the point socket of said member D should be made in accordance with the requirements in any particular case as regards the shape, or particular conical formation, of pencil point which may be desired. An advantage of this form of expanding or separating member is, that while it provides for sharpening or pointing the lead of the pencil by the same cutting-edge that cuts the wood or lead-encasing portion of the pencil, and also acts as a means for separating the knife-edge and plane-edge of the cone, it is simple in construction and can be easily and cheaply made.

Having thus described my invention, I claim:

1. A pencil sharpener comprising a split tubular cone for receiving the lead pencil therein, the split edge portions of the cone providing a plane edge and a knife edge, and means for positioning the plane edge and knife edge for co-action therebetween for cutting by the knife edge.

2. A pencil sharpener comprising a split tubular cone for receiving the lead pencil therein, the split edge portions of the cone providing a plane edge and a knife edge, and means for positioning the plane edge and knife edge for coaction therebetween for cutting by the knife edge, the knife edge providing a binding spring for retaining the means for positioning in the tubular cone.

3. A pencil sharpener comprising a split

tubular cone for receiving the lead pencil therein, the split edge portions of the cone providing a plane edge and a knife edge, and means for positioning the plane edge 5 and knife edge for co-action therebetween for cutting the encased end of the lead pencil by the knife edge, said means for positioning the knife edge forming an opening at the mouth of the tubular cone for inserting 10 therein the unencased lead of the pencil for pointing said lead by the knife edge.

4. A pencil sharpener comprising a split tubular cone for receiving the lead pencil therein, the split edge portions of the cone 15 providing a plane edge and a knife edge, and means for positioning the plane edge and knife edge for coaction therebetween for cutting the encased end of the lead pencil by the knife edge, the knife edge providing a binding spring for retaining the 20 means for positioning in the tubular cone, and said means for positioning and the knife edge forming an opening at the mouth of the tubular cone for insertion therein of the 25 unencased lead end of the pencil for pointing said end by the knife edge.

5. A pencil sharpener comprising a split tubular cone for receiving the lead pencil therein, the split edge portions of the cone 30 providing a plane edge and a knife edge, and means located between the plane edge and the knife edge having ends engaging the plane edge and knife edge for positioning said edges for coaction therebetween for cutting by the knife edge.

6. A pencil sharpener comprising a split tubular cone for receiving the lead pencil therein, the split edge portions of the cone providing a plane edge and a knife edge, and 40 means located between the plane edge and the knife edge having ends engaging the plane edge and knife edge for positioning said edges for coaction therebetween for cutting by the knife edge, the knife edge providing a binding spring for retaining the 45 means for positioning in the tubular cone.

7. A pencil sharpener comprising a split tubular cone for receiving the lead pencil therein, the split edge portions of the cone 50 providing a plane edge and a knife edge, and means located between the plane edge and the knife edge having ends engaging the plane edge and knife edge for positioning said edges for coaction therebetween for cutting the encased end of the lead pencil by the knife edge, said means for positioning and the knife edge forming an opening at the mouth of the tubular cone for insertion 55 therein of the unencased lead end of the pencil for pointing said end by the knife edge.

8. A pencil sharpener comprising a split tubular cone for receiving the lead pencil therein, the split edge portions of the cone 60 providing a plane edge and a knife edge, and

means located between the plane edge and the knife edge having ends engaging the plane edge and knife edge for positioning said edges for coaction therebetween for cutting the encased end of the lead pencil by the 70 knife edge, the knife edge providing a binding spring for retaining the means for positioning in the tubular cone, and said means for positioning and the knife edge forming an opening at the mouth of the tubular cone 75 for insertion therein of the unencased lead end of the pencil for pointing said end by the knife edge.

9. A pencil sharpener comprising an expansively resilient tubular cone for receiving the lead pencil therein provided with a plane-edge having a recess therein and provided with a knife-edge for cutting the lead-encasing portion of the pencil, a separating member provided with curved ends and provided with means for engaging said recess between the blank and edge, one of said ends when said member is in engagement with said recess being in engagement with the exterior surface of said plane-edge and 80 the other of said ends being in engagement with the interior surface of said knife-edge for pressing the knife-edge outwardly, and means for guiding the lead pencil in the tubular cone for cutting the lead-encasing 85 portion thereof.

10. A pencil sharpener comprising an expansively resilient tubular cone for receiving the lead pencil therein provided with a plane-edge having a recess therein and provided with a knife-edge for cutting the lead-encasing portion of the pencil, a separating member provided with curved ends and provided with means for engaging said recess, one of said ends when said member is in engagement with said recess being in engagement with the exterior surface of said plane-edge, and the other of said ends being in engagement with the interior surface of said knife-edge for pressing the knife-edge 95 outwardly, and means for guiding the lead pencil in the tubular cone for cutting the lead-encasing portion thereof; said outwardly pressing end and said knife-edge when said member is in engagement with said recess providing a socket for receiving the lead-end of the pencil for pointing the lead-end by said knife-edge.

11. A pencil sharpener comprising an expansively resilient tubular cone for receiving the lead pencil therein provided with a plane-edge having a straight face and having a recess therein and provided with a knife-edge having a cutting-edge for cutting the lead-encasing portion of the pencil, a 100 separating member provided with curved ends and provided with a rib for engaging said recess and the interior surface of said plane-edge, one of said curved ends when said rib is in engagement with said recess 105

and the interior surface of said plane-edge being in engagement with the exterior surface of the plane-edge and a first face of the other of said curved ends being in engagement with said straight face of the plane-edge and a second face thereof being in engagement with the interior surface of said knife-edge for pressing the same outwardly and a third face thereof being in engagement with said cutting-edge as a stop-face for said cutting-edge, and guide-springs in the tubular cone for the lead pencil.

12. A pencil sharpener comprising an expansively resilient tubular cone for receiving the lead pencil therein provided with a plane-edge having a straight face and having a recess therein and provided with a knife-edge having a cutting-edge for cutting the lead-encasing portion of the pencil, a separating member provided with curved ends and provided with a rib for engaging said recess and the interior surface of said plane-edge, one of said curved ends when said rib is in engagement with said recess and the interior surface of said plane-edge being in engagement with the exterior surface of said plane-edge, and a first face of the other of said curved ends being in engagement with said straight face of the plane-edge and a second face thereof being in engagement with the interior surface of said knife-edge for pressing the same outwardly and a third face thereof being in engagement with said cutting-edge as a stop-face for said cutting-edge, and guide-springs in the tubular cone for the lead pencil; said outwardly pressing face and said knife-edge when said rib is in engagement with said recess and the interior surface of said plane-edge providing a socket for receiving the lead of the pencil for pointing the lead by said cutting-edge.

13. A pencil sharpener comprising an expansively resilient tubular cone for receiving the lead pencil therein provided with a plane-edge having a straight face and having a recess therein and provided with a knife-edge having a cutting-edge for cutting the lead-encasing portion of the pencil, a separating member provided with reversely curved ends and provided with a rib for engaging said recess and the interior surface of said plane-edge, one of said curved ends when said rib is in engagement with said recess and the interior surface of said plane-edge being in engagement with the exterior surface of said plane-edge, and a first face of the other of said curved ends being in engagement with said straight face of the plane-edge and a second face thereof being in engagement with the interior surface of said knife-edge for pressing the same outwardly and a third face thereof being in engagement with said cutting-edge as a stop-face for said cutting-edge, and guide-springs

in the tubular cone for the lead pencil, said guide-springs being integral with the tubular cone.

14. A pencil sharpener comprising an expansively resilient tubular cone for receiving the lead pencil therein provided with a plane-edge having a straight face and having a recess therein and provided with a knife-edge having a cutting-edge for cutting the lead-encasing portion of the pencil, a separating member provided with reversely curved ends and provided with a rib for engaging said recess and the interior surface of said plane-edge, one of said curved ends when said rib is in engagement with said recess and the interior surface of said plane-edge being in engagement with the exterior surface of said plane-edge, and a first face of the other of said curved ends being in engagement with said straight face of the plane-edge and a second face thereof being in engagement with the interior surface of said knife-edge for pressing the same outwardly and a third face thereof being in engagement with said cutting-edge as a stop-face for said cutting-edge, and guide-springs in the tubular cone for the lead pencil, said guide-springs being integral with the tubular cone; said outwardly pressing face and said knife-edge when said rib is in engagement with said recess and the interior surface of said plane-edge providing a socket for receiving the lead-end of the pencil for pointing the lead-end by said cutting-edge.

15. A pencil sharpener comprising a resilient split cone, the split edge portions thereof providing a plane-edge and a cutting-edge, said cone being formed for said cutting-edge to have a position within the circle of its proper cutting position, and a cone-expanding member interlocked with said edge and provided with faces for locating said cutting-edge in cutting position.

16. A pencil sharpener comprising a resilient split cone, the split edge portions thereof providing a plane-edge and a cutting-edge, said cone being initially formed for said cutting-edge to have a position within the circle of its proper cutting position, and a cone-expanding member interlocked with said edge and provided with faces for locating said cutting-edge in proper cutting position.

17. A pencil sharpener comprising a resilient split cone, the split edge portions thereof providing a plane-edge and a cutting-edge, said cone being formed for said cutting-edge to have a cutting position within the cone circle, and a cone-expanding member separable from the cone interlocked with said edge and provided with faces for locating said cutting-edge in normal cutting position.

18. A pencil sharpener blank of resilient

metal of truncated segment of a circle shape, one edge of said segment being non-cutting and provided with a recess therein adjacent to the periphery of the segment, the other edge thereof being a knife edge, and the blank being provided with a pair of cuttings therethrough having parallel sides extending longitudinally of the blank, the cuttings at one end of the sides thereof being connected to the blank, for forming cooperating guide-springs.

19. A pencil sharpener blank of resilient metal of truncated segment of a circle shape, the truncated end of the segment being concave, one edge of said segment being non-cutting and provided with a recess therein adjacent to the periphery of the segment, the other edge thereof being a knife edge and the blank being provided with a pair of cuttings therethrough, each cutting having parallel sides extending longitudinally of the

blank, the cuttings at one end of the sides thereof being connected to the blank, for forming cooperating guide-springs.

20. A pencil sharpener blank of resilient metal of truncated segment of a circle shape, one edge of said segment being provided with a straight face having a recess therein adjacent to the periphery of the segment, and the other edge thereof being a knife edge having a cutting edge thereon, and the blank being provided with cuttings therethrough having rounded ends and parallel sides, the cuttings at the ends of the sides thereof opposite to said rounded ends being connected to the blank, for forming cooperating guide-springs.

CLEMENT CLEVELAND.
